Primary Examiner — Rosemary Tarcza*Assistant Examiner* — Christy Nemeth(57) **CLAIM**

The ornamental design for a cell box, as shown and described.

DESCRIPTION

FIG. 1 is a perspective view of a first embodiment of a cell box showing our new design;

FIG. 2 is a front elevational view of FIG. 1;

FIG. 3 is a rear elevational view of FIG. 1;

FIG. 4 is a left side view of FIG. 1;

FIG. 5 is a right side view of FIG. 1;

FIG. 6 is a top plan view of FIG. 1;

FIG. 7 is a bottom plan view of FIG. 1;

FIG. 8 is a perspective view of FIG. 1 in an open state;

FIG. 9 is a perspective view of a second embodiment of a cell box;

FIG. 10 is a front elevational view of FIG. 9;

FIG. 11 is a rear elevational view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9; and,

FIG. 16 is a perspective view of FIG. 9 in an open state.
